Application June 16, 1949, Serial No. 99,372

8 Claims. (Cl. 51—101)

1

This invention relates to optical lens grinding machines, and more particularly to a machine for edging a lens blank.

The invention, in general, is embodied in a machine having a lens blank holding means, an abrading element for grinding the edge of the lens blank, pattern means for determining the peripheral shape of the lens blank, means for controlling the movement of these members in a predetermined manner, and means for driving the machine.

One of the objects of the invention is to provide a support for mounting the lens blank element so that the peripheries of the lens blank and the abrading element can be brought into contact. This support is free floating and provides for moving the lens blank element toward and away from the other element. The support also cooperates with means for causing relative translatable movement of these elements while their peripheral surfaces are in abrading relation with one another.

A feature of this construction is that a small, lightweight and compact machine can be provided which is adapted for either dry edging plastic lenses with an abrasive belt, for example, or for grinding glass lenses with a small and inexpensive diamond wheel. It has been found impractical from a cost standpoint to equip a standard lens edging machine with a diamond wheel of the usual or regular size. The construction here provided is adaptable for using an extremely small size of diamond wheel which is both practical and economical. With the latter construction, the machine is equipped with a small pump and coolant reservoir which replaced the suction pump provided to remove the dust or cuttings resulting from dry edging plastic lenses. Furthermore, in addition to cutting a square edge for rimless mountings, the machine can also be adapted to edge lenses for frame mountings since it can cut a bevelled edge when provided with an abrading element which cuts a V-shaped section around the periphery of the lens blank.

An additional object of the invention is to provide an arm for rotatably supporting the driven lens blank element, the arm being swingable on a pivot means for movement of the lens blank element toward and away from the abrading element, as well as for longitudinal movement relative to the abrading element. A feature of this construction is that the lens blank element and the pattern means, for determining the peripheral contour of the lens blank, can be swung so that the lens blank crosses the abrading element

with its axis of rotation parallel to the axis of rotation of the abrading element, and while so moving the lens blank is free to move in a direction at right angles to said axes of rotation in response to movement of the pattern means.

Another object of the invention is to provide a cam and cam follower, as part of the pattern means, for controlling the movement of the lens blank element whereby the lens blank is gradually lowered into contact with the abrading element. This feature of the construction prevents a deep cut being taken too rapidly from the lens blank, such as would occur if the lens blank element under the full weight of the supporting arm remained continuously in contact with the abrading element. In operation, the lens blank while being edged is raised and lowered, with respect to the abrading element, in response to movement of the cam follower. This movement prevents the lens blank from being heated excessively and its optical properties are not distorted. A further feature resulting from this construction is that the lens blank is moved across substantially the entire surface of the abrading element, thus assuring even wear across the entire peripheral surface of the abrading element.

An additional object is to provide a driving means, such as a pulley and endless belt, for applying power from a prime mover to rotate the lens blank and associated mechanism, in which the belt pull or torque is applied at a point which, when projected, lies in a plane extending at right angles to the axis of rotation of the pulley, and which plane also extends through the projected axis of rotation about which the pivotally mounted support for the lens blank element moves. The support is thus free floating in that the support at all times pivots about a point in line with the belt pull.

It is also another object to provide pattern means for controlling the peripheral configuration of the lens blank, which comprises a cam member and a pattern member, and which are translatable movable with respect to one another. Means in the form of a feed screw and an engaging element are provided for causing movement between these members. A feature of this construction resides in having the feed screw driven from the same shaft means provided for driving the pattern member. The feed screw is also utilized to control the rate at which the lens blank is moved into abrading relation with the abrading element. The regulation thus

effected prevents the lens blank from being cut to pattern size at a rate which causes excessive heating thereof.

Other features of this invention reside in providing an abrading element in the form of a drum adapted to receive an abrasive belt having a surface of silicon carbide grit or similar material. The drum is driven at a high rate of speed, of the order of 5000 R. P. M., and the lens holder at a low rate of speed, of the order of 2 R. P. M. 5 Also, if desired, the suction pump for removing the dust or cuttings from the grinding operation can be driven from the same power source provided for driving the lens blank, or a pump can be operated therefrom to circulate a coolant where a diamond wheel is used.

Further objects and advantages of the present invention will be apparent from the following description, reference being had to the accompanying drawings wherein preferred forms of 20 embodiments of the invention are clearly shown.

In the drawings:

Fig. 1 is a top plan view of a machine embodying one form of the present invention;

Fig. 2 is a side elevational view of the machine 25 shown in Fig. 1;

Fig. 3 is a front elevational view of the machine as seen from the right side of Fig. 2;

Fig. 4 is a side elevational view, partly in section, of the switch and mounting mechanism 30 therefor;

Fig. 5 is a broken, back elevational view, partly in section, showing the pivotal connections between the arm and base, and a part of the shaft driving means, as seen from the left end in Fig. 1; 35

Fig. 6 is a broken, vertical sectional view, partly in elevation, showing the lens holder, pattern means and feed screw as carried by the arm;

Fig. 7 is a diagrammatic view illustrating the 40 positioning of the link, shaft and pulley relative to the pivotal connection between the link and the base;

Fig. 8 is an elevational view of the cam and supporting bracket as seen from the right side in Fig. 3; and

Figs. 9 to 11 are diagrammatic views illustrating 45 modified constructions of the cam shoe and abrading element for bevel edging the edge of the lens blank.

Referring further to the drawings, the machine shown includes a supporting base 10. A support, indicated generally at 11, includes a link 12, an arm member 13, and a second arm member 14 integral with member 13 and at right angles thereto. One end of member 13, as seen in Fig. 5, is pivotally mounted within the U-shaped yoke 15.

A shaft 16 extends through member 13 and yoke 15. This shaft is journaled at each end in the bearings 17. These bearings are mounted so as to be carried by both the yoke and member 13, as shown. There is a press fit of the bearing 17 in member 13 and a running fit of the bearing 17 in the yoke 15. Sufficient clearance is provided between the yoke and member 13 to allow free swinging movement of member 13 about the shaft 16 in a plane at right angles to the base 10.

The yoke 15 is slidably mounted at the bottom on the seat 20 formed on the base. A pair of oval shaped openings 21 extends through the top of the base and seat 20. The screws 22, Fig. 5, engage the bottom of the yoke 15 through these openings. These screws also connect the yoke to the link 12 which, in turn, is pivotally connected with a screw at its outer end to the base, as indicated at 24. Movement of the yoke 15 75

on the seat 20 is controlled by the movement of the link 12 about the pivot 24.

Transmission means is provided which comprises, in general, the shaft 16, a shaft 27 extending longitudinally through arm member 13, and a spindle shaft 28 carried by the arm member 13. These shafts are rotatably mounted and driven by a pulley 30 connected to the shaft 16. Shaft 16 drives shaft 27 through a worm 31 and gear 32, Fig. 5. Shaft 27, in turn, drives shaft 28 through a worm 33 and gear 34, Fig. 6. Thrust bearings 35, Fig. 2, are provided at each end of shaft 27. The shaft 28 is journaled for rotation within the bearings 36 and 37 which extend through the inner end of arm member 13. Power is transmitted from the motor 38, Fig. 2, which is provided with a driving wheel, through the belt 39 from the driving wheel to the pulley 30.

The axis of pivot 24, when projected upwardly, substantially intersects the peripheral edge of the pulley 30 substantially most remote from the free end of arm 13 and from the driving pulley of motor 38. Referring to the diagram of Fig. 7, the arrangement of the arm members, i. e., link 12, shaft 16 and pulley wheel 30 with respect to the pivot 24 are shown. This construction provides for a free floating arm which is unaffected by the pulling action of the belt 39 on the pulley 30 and shaft 16. The force or pull of the belt 39 is thus applied in the direction of the arrow 43, Fig. 7, and at a point in the plane extending through the pulley 30 at right angles to its axis of rotation and through the projected axis of rotation of the pivot 24. The application of this force in that plane does not cause a turning or moving force to be exerted on the members 13 and 15. The arm 14 is thus free to swing in a plane parallel to the top of base 10. Furthermore, with this construction the length of arm 13, i. e. the radius of the arc through which the arm 14 swings parallel to the top of base 10, can be made a maximum within the prescribed size limits of the machine. The axes of rotation of the lens blank holder, pattern means and the abrading element, as hereafter described, can thus be maintained in substantially parallel alignment during the cutting or edging operations. This construction also provides for leading the belt 39 from the motor driving pulley onto the pulley 30 at a point which does not swing out of the plane extending through the pulley 30 at right angles to the axis of rotation of the pulley 30 and through the projected axis of rotation of the pivot 24. The belt 39 thus remains on the pulley 30 when the supporting members 13, 14 and 15 swing about the pivot 24.

In the preferred construction an electric motor of about $\frac{1}{6}$ horsepower capacity and capable of rotation at 5000 R. P. M. is provided. This speed of rotation is reduced through the gearing mechanism provided so that the shaft 28 rotates at a rate of about 2 R. P. M.

A lens holder is provided for mounting the lens blank 42, Fig. 3, in working position. The holder includes a positioning member 43 which is received on the pins 44, Fig. 6, which project from the head 45 formed on the end of shaft 28. Member 43 thus rotates with the shaft 28. 65 Member 43 also forms part of the holder. This pad is positioned to engage the lens blank on the opposite side from member 43. The pad is faced with a rubber washer 48 on the front and engages at the back with a ball bearing 49. Bearing 49 is rotatably mounted on the

compression shaft 51 and the pad 47 rotates with the lens blank. Shaft 51 is received within the bearing 52 carried in the outer end of arm member 14. A pin 53, Fig. 6, on the head of shaft 51 projects through a slot in the edge of bearing 52. This pin prevents rotation of the shaft 51. A coil spring 54 encircles the shaft and seats against the head at one end and against the inner end of bearing 52 at the other. This spring forces the pad 47 against the lens blank. The outer end of shaft 51 is threaded to receive a knurled knob 55. This knob is adjustable and provides for moving the shaft 51 and pad 47 toward and away from the lens blank for either positioning or removing the lens blank in the holder. A stop nut 56 on the end of shaft 51 prevents the knob 55 from backing off the shaft. A set screw 57 retains the bearing 52 in the arm.

A shaft extension member 61 is coupled to the end of shaft 28. This member is formed with pins 62 fitting in openings in the cam follower for positioning the cam follower, indicated at 63 in Figs. 3 and 6, which forms part of the pattern means for determining the peripheral shape or contour imparted to the lens blank 42. In operation, a follower 63 is used which has a peripheral shape or contour of either regular or irregular form, and to which form the lens blank 42 is patterned when edged. The follower 63 is rotatably driven by member 61. A threaded shank 64, projecting from the outer end of member 61, extends through a central opening in the follower. A tapered and externally threaded section in the form of a feed screw 67 is threadedly connected to the shank 64 and driven thereby from shaft 28. The body of the screw is threaded as shown at 67a, Fig. 1, and the head knurled, as indicated at 67b, Fig. 6, to facilitate mounting on shank 64. Screw 67 retains the follower 63 on the pins 62. The outer end of the screw forms a bearing area 68 having a flanged head 69.

Referring further to Figs. 1 and 4, the base 10 is formed with a boss 71. This boss is drilled to receive a spring pressed cap 72. At right angles to this bore, the boss is drilled to receive a short rod 73 which fastens a hinge member 74 to the boss. The hinge 74 carries the knife arm or lever 75 to which the knife blade 76 is adjustably attached. The edge of the blade 76 is bent inwardly, as shown, and forms an element adapted to engage the threads on the feed screw 67 when arm member 14 is in operating position. The spring pressed cap 72 bears against the lower end of the pivotally mounted lever 75 and holds the knife blade 76 in engagement with the threads on the body of the feed screw. An arm 78 is connected to the lower end of the lever 75. This arm extends through an opening 79 in the top of the base 10. A switch 80 having a push button 80a is provided to control the starting and stopping of motor 38. Switch 80 is open when the button 80a is depressed. Thus, when the arm 14 is set so that the threads on the feed screw 67 engage with the blade 76, the lever 75 is pivoted inwardly at the bottom, i. e., moves clockwise and against the cap 72. This movement causes the arm 78 to move away from button 80a whereby the switch closes to start the motor. When the arm 14 is driven to a point where the blade 76 disengages from the threads on the feed screw and engages the bearing area 68 and the spring cap 72 moves lever 75 counterclockwise and arm 78 depresses but-

ton 80a. Switch 80 then opens and stops the motor.

The follower 63 engages with and rotates upon a cam means 81. This cam controls the movement of the follower in a direction perpendicular to its axis of rotation. The cam means 81 includes a bracket 82 screwed to the top of the base 10, Figs. 1, 3 and 8. An adjusting screw 82b cooperates with a knurled nut 83 and extends up through the top of base 10 and through the bracket. The cam shoe 84 is fastened to the top of the adjusting screw 82b and is raised or lowered relative to the bracket when the nut 83 is adjusted. This shoe is formed with a declining surface 84a (Fig. 3) extending longitudinally in the direction of the axis of rotation of the follower 63. This surface forms an arc of a curve extending transversely to the axis of rotation of the follower 63, as indicated at 84b in Fig. 8. In operation, the periphery of the follower 63 is placed first in contact with the high portion of the cam shoe 84. As the feed screw 67 drives the arm 14, the follower moves down over the surface 84a of the shoe from the high to the low point and gradually lowers the arm and lens blank.

The abrading element for the lens blank comprises, in general, a quill housing 91 having a centrally positioned spindle shaft 92, Fig. 3. This shaft is secured at one end within the upper part of the base 10. The quill housing 91 is supported at each end on bearings 93 mounted on the shaft 92. This quill housing 91 thus rotates freely. The quill housing 91 is enlarged to provide a drum portion 94 which is encircled by a removable abrasive belt 95. This belt is substantially the full width of the drum as shown in Fig. 3. In one form, this belt is constructed of a heavy fabric-like material having a coating of silicon grit on its outer surface. The belt is held on the drum by the end flange member 97 which is fastened to the end of the drum with screws. The drum 94 is constructed with a peripheral curve having substantially the same radius of curvature as the arc of surface 84b (Fig. 8) on the cam shoe so that the lens blank will be edged to conform to the pattern of the follower 63. If desired, a diamond wheel of the same size can be substituted for the drum 94 and belt 95.

A groove is formed in the opposite end of the quill housing 91 to receive a belt 101. This belt is directly driven from the motor 38 and rotates the drum at a rate of speed of the order of 5000 R. P. M. The shaft means for driving the holder 55 provides for rotating the lens blank in a direction opposite to the direction of rotation of the drum 94 and at a rate of speed of the order of 2 R. P. M. Then when the edge of the lens blank 42 comes into contact with the abrasive surface 95 of the belt 95, a cutting engagement is obtained.

A suction pump 105, Fig. 3, is also driven from the motor 38. A recessed area 106 is provided in the top of the base beneath the drum 94 to receive the cuttings and dust from the grinding operations. These cuttings are removed through an opening in the surface 106 which connects with an adapter 107. A hose, not shown, connects between the adapter and the suction inlet 108 of the pump.

In Fig. 9 a modified construction is illustrated. This construction is adapted to provide for bevel edging the lens blank 42. The feed screw 67 is provided with a second bearing surface 115 terminating in a head 116. The cam shoe surface 84a is extended to provide a recessed horizontal

surface 117. In addition to the abrading element 95 another abrading element 95a having a V notch cutting surface 118 is provided. The over-all depth of the notch 118 is equal to or slightly greater than the distance which the surface 117 is below the surface 119 of the cam shoe so that the over-all diameters of the lens blank will not be changed by further cutting. In operation, when the follower 63 reaches the lowest part of the cam surface 84a, i. e., surface 119, the lens blank 42 has moved across the surface 95 of the abrading element and is cut down to the desired shape and dimensions. Further movement of the arm 14 is prevented by engagement of blade 76 with the head 69. The arm 14 is raised by the operator to free blade 76 from engagement with head 69 and the arm swung horizontally so that blade 76 engages between the heads 69 and 116. This movement is sufficient to bring the follower 63 into engagement with the surface 117 and to center the lens blank 42 in the V-notch 118 of the abrading element 95a. Rotation of the abrading element cuts a bevel edge on each side of the lens blank.

A further modification is shown in Fig. 10. In this form, the bevel edge can be completed as a continuous part of the cutting operations. The cam sole surface 84a is extended to provide a downwardly sloping surface 120 terminating in a horizontal surface 121 having a stop member 122. Where, for example, the bevel on the lens blank is to be 45 degrees, the slope of surface 120 is 22½ degrees from vertical. The abrading element 95a is provided with a V-notch 118a having oppositely disposed sides 123 and 123a sloping at 45 degrees. The over-all depth of the notch 118a is equal to the depth of the cam surface 121 below surface 119 so that the cutting to produce the bevel edges does not reduce the over-all finished diameters of the lens blank. In operation, the follower 63 moves from the surface 119 down the slope of surface 120. This movement causes the lens blank to move down the slope of surface 123a and the rotation of the abrading element produces a bevel edge on one side of the lens blank. As the follower 63 moves across surface 121, the other side of the lens blank is brought into contact with the surface 123 which produces a bevel edge on that side of the lens blank. Engagement of the follower 63 with the stop member 122 prevents the lens blank from being too deeply cut or bevelled by engagement with surface 123.

Another form of construction for bevel edging is shown in Fig. 11. The cam shoe 84 is provided with a surface 124 which slopes upwardly at 30 degrees from horizontal where the bevel edge is to be at 45 degrees. A horizontal surface 126 and an oppositely disposed surface 128 sloping at 22½ degrees from vertical are also provided. The abrading element 95a is provided with a surface 130 sloping upwardly at 45 degrees, a horizontal surface 131 and a surface 132 at 45 degrees oppositely disposed from surface 130. In operation, as the follower 63 moves up the surface 124 the lens blank is brought into contact with surface 130 and gradually cut down to the desired overall dimensions and shape. As shown, the lens blank edge in contact with surface 130 will be cut at an angle of 45 degrees. Movement of the follower across surface 126 provides for removing any tail that may be formed from the cutting on surface 130. Movement of the follower across surface 126 carries the lens blank across surface 131. Further movement of the

follower down the surface 128, i. e., at 22½ degrees, brings the other edge of lens blank into contact with the 45 degree surface 132 and produces a finished bevel of 45 degrees on that edge.

In operation, the arm 14 is raised manually and swung back at right angles to the top of base 10. Such movement disengages the feed screw 67 from the knife blade 76. The lever 75 is then moved by the spring caps 72 to a position opening the switch and stopping motor 38. In the raised position the underside of arm member 14 is exposed. This facilitates either mounting or removing a lens blank.

When a lens blank is mounted in the holder, the arm 14 is lowered from the raised position. The arm 14 is swung parallel to the top of base 10 until the follower 63 rides on the high part of the cam shoe 84. The knife blade 76 is adjusted so that in this position it then engages between the threads at the end of the feed screw 67 farthest from the head 69. This engagement moves the lever 75 in a direction which causes the motor switch to close. The motor, in turn, drives the shafts 16, 27 and 28, the quill 91, and the blower 105. Shaft 28 rotates both the lens holder and the follower, and drives the feed screw 67. The rotation of the feed screw, while in engagement with the knife blade 76, causes the support 11 to move about the pivot 24. This movement causes the rotating follower 63 to move gradually down the surface 84a of the cam shoe. The lens blank rotates in synchronism with the follower and is also responsive to the movement of the follower at right angles to its axis of rotation, since the supporting arm 13 is free to pivot about shaft 16. This construction provides for gradually cutting the lens blank down to the desired shape as the lens blank moves down into contact with the rotating belt 95 and across the belt from one edge thereof to the other. As the edging of the lens blank progresses, the arm 14 swings in an arc about the pivot 24. The radius of this arc is such that when the edging of the lens blank is completed the axis of rotation of shaft 28, carrying the lens blank and follower, is parallel to the axis of rotation of the abrading element. This construction provides for accurately edging the lens blank according to the pattern of the follower.

When the follower moves across the low part of the cam shoe surface 84a, the edging of the lens blank is completed. The arm 14 has then moved a sufficient distance for the threads on the feed screw to disengage from the knife blade 76. Blade 76 then engages adjacent the bearing area 68 and head 69 prevents further longitudinal movement of the screw with respect to the blade 76. The lever 75 then is no longer held in a position to maintain the motor switch closed and the motor stops. The operator then raises the arm 13 to remove the finished lens blank, inserts a new lens blank, and again lowers the arm to repeat the operation.

While the forms of embodiments of the present invention as herein disclosed constitute preferred forms, it is to be understood that other forms might be adopted, all coming within the scope of the claims which follow.

We claim:

1. In a lens edging machine, in combination, a base; an abrading element; a rotating shaft carried by the base and carrying the abrading element; a second rotating shaft having a threaded portion; a lens blank holding element

carried by the second shaft; means for rotatably supporting the second shaft with the axis thereof substantially parallel with the axis of the first shaft, said means including a pivot on the base having an axis disposed substantially at right angles to the axis of the first shaft, and an arm pivotally mounted on the pivot and extending toward the first mentioned shaft and carrying the second mentioned shaft; a member on the base received by the groove of the threaded portion of the second shaft, for causing swinging movement to be imparted to the arm when the second shaft is rotated; and means for rotating the shafts.

2. In a lens edging machine, in combination, a base; an abrading element; a rotating shaft carried by the base and carrying the abrading element; a second rotating shaft having a threaded portion; a lens blank holding element carried by the second shaft; means for rotatably supporting the second shaft with the axis thereof substantially parallel with the axis of the first shaft, said means including a pivot on the base having an axis disposed substantially at right angles to the axis of the first shaft, and an arm pivotally mounted on the pivot, said arm including a pivot disposed on an axis transverse to the axis of the first mentioned pivot and including a lever pivotally carried by the second mentioned pivot and extending toward the first mentioned shaft and carrying the second mentioned shaft; a member on the base received by the groove of the threaded portion of the second shaft, for causing swinging movement to be imparted to the arm when the second shaft is rotated; and means for rotating the shafts.

3. In a lens edging machine, in combination, a base; an abrading element; a rotating shaft carried by the base and carrying the abrading element; a second rotating shaft having a threaded portion; a lens blank holding element carried by the second shaft; means for rotatably supporting the second shaft with the axis thereof substantially parallel with the axis of the first shaft, said means including a pivot on the base having an axis disposed substantially at right angles to the axis of the first shaft and an arm pivotally mounted on the pivot, said arm including a rotating driving shaft disposed on an axis transverse to the axis of the pivot, said arm including a lever pivotally carried by the last mentioned shaft and extending toward the first mentioned shaft and carrying the second shaft; gearing between the shafts carried by the arm; a member on the base received by the groove of the threaded portion of the second shaft for causing swinging movement to be imparted to the arm when the second shaft is rotated; and means for rotating the shafts.

4. In a lens edging machine, in combination, a base; an abrading element; a rotating shaft carried by the base and carrying the abrading element; a second rotating shaft having a threaded portion; a lens blank holding element carried by the second shaft; means for rotatably supporting the second shaft with the axis thereof substantially parallel with the axis of the first shaft, said means including a pivot on the base having an axis disposed substantially at right angles to the axis of the first shaft, and an arm pivotally mounted on the pivot, said arm including a bearing support slidably carried on the base, said arm including a shaft carried by the bearing support, the last mentioned shaft being

disposed on an axis transverse to the axis of the first mentioned pivot, said arm including a lever pivoted on an axis transverse to the axis of said pivot and extending toward the first mentioned shaft and carrying the second shaft; gearing between the shafts carried by the arm; a member on the base received by the groove of the threaded portion of the second shaft for causing swinging movement to be imparted to the arm when the second shaft is rotated; and means for rotating the shafts.

5. In a lens edging machine, in combination, a base; an abrading element; a rotating shaft carried by the base and carrying the abrading element; a second rotating shaft; a lens blank holding element carried by the second shaft; means for rotatably supporting the second shaft with the axis thereof substantially parallel with the axis of the first shaft, said means including a pivot on the base having an axis disposed substantially at right angles to the axis of the first shaft, and an arm pivotally mounted on the pivot, said arm including a bearing support slidably carried on the base, said arm including a rotating driving shaft carried by the bearing support and disposed on an axis transverse to the axis of the pivot and intermediate the pivot and the first mentioned shaft, said arm including a lever pivoted on the arm on an axis transverse to the axis of said pivot and extending toward the first mentioned shaft and carrying the second mentioned shaft; gearing between the shafts carried by the arm; a driving wheel on the third mentioned shaft; a belt on the wheel; and means for driving the belt, the axis of the pivot of the arm when projected substantially intersecting the peripheral portion of the wheel at a point substantially most remote from the means for driving the belt.

6. In a lens edging machine, in combination, a base; an abrading element; a rotating shaft carried by the base and carrying the abrading element; a second rotating shaft; a lens blank holding element carried by the second shaft; means for rotatably supporting the second shaft with the axis thereof substantially parallel with the axis of the first shaft, said means including a pivot on the base having an axis disposed substantially at right angles to the axis of the first shaft, and an arm pivotally mounted on the pivot and extending toward the first mentioned shafts, said arm including a bearing support slidably carried on the base, a rotating driving shaft carried by the bearing support and disposed on an axis transverse to the axis of the pivot and intermediate the pivot and the first mentioned shaft; gearing between the shafts carried by the arm; a driving wheel on the third mentioned shaft; a belt on the wheel; and means for driving the belt, the axis of the pivot of the arm when projected substantially intersecting the peripheral portion of the wheel at a point substantially most remote from the means for driving the belt.

7. In a lens edging machine, in combination, a base; an abrading element; a rotating shaft carried by the base and carrying the abrading element; a second rotating shaft having a threaded portion; a lens blank holding element carried by the second shaft; means for rotatably supporting the second shaft with the axis thereof substantially parallel with the axis of the first shaft, said means including a pivot on the base having an axis disposed substantially at right angles to the axis of the first shaft, and an arm

11

pivotedly mounted on the pivot and extending toward the first mentioned shaft and carrying the second mentioned shaft; means for rotating the second mentioned shaft; and mechanism for controlling the last named means including a controller having a member received by the groove of the threaded portion of the second mentioned shaft and movable to effect starting and stopping of the shaft rotating means by engagement and disengagement, respectively, of the threaded portion of the second mentioned shaft with said member.

8. In a lens edging machine, in combination, a base; an abrading element; a rotating shaft carried by the base and carrying the abrading element; a second rotating shaft having a threaded portion; a lens blank holding element carried by the second shaft; means for rotatably supporting the second shaft with the axis thereof substantially parallel with the axis of the first shaft; said means including a pivot on the base having an axis disposed substantially at right angles to the axis of the first shaft, and an arm pivotally mounted on the pivot, said arm including a pivot disposed on an axis transverse to the axis of the first mentioned pivot and including a lever pivotally carried by the second mentioned

12

pivot and extending toward the first mentioned shaft and carrying the second mentioned shaft; means for rotating the second mentioned shaft; and mechanism for controlling the last named means including a controller having a member received by the groove of the threaded portion of the second mentioned shaft and movable to effect starting and stopping of the shaft rotating means by engagement and disengagement, respectively, of the threaded portion of the second mentioned shaft with said member.

ROBERT E. ALLEN.
